UNITED STATES PATENT OFFICE.

JONATHAN P. B. FISKE, OF LYNN, ASSIGNOR TO THE GENERAL ELECTRIC COMPANY, OF BOSTON, MASSACHUSETTS.

RHEOSTAT FOR CONTROLLING ELECTRICALLY-OPERATED DENTAL APPARATUS.

SPECIFICATION forming part of Letters Patent No. 508,692, dated November 14, 1893.

Application filed July 10, 1893. Serial No. 479,992. (No model.)

To all whom it may concern:

Be it known that I, JONATHAN P. B. FISKE, a citizen of the United States, residing at Lynn, in the county of Essex and State of Massachusetts, have invented certain new and useful Improvements in Rheostats for Controlling Electrically-Operated Dental Apparatus, of which the following is a specification.

My invention relates to rheostats for controlling electrically operated dental apparatus, and has for its object to provide a controller of efficiency and simplicity in construction and operation and one capable of being used continuously without fatigue to the operator.

My invention is illustrated in the accompanying drawings, hereby referred to and made part of this specification, in which—

Figure 1 is a side elevation partly in section. Fig. 2 is a plan with one-half the top broken away and showing the brush-holder in section, and Fig. 3 is a side elevation partly in section, at right angles to the view in Fig. 1. Fig. 4 is a diagram of the connections of the motor field magnets and armature.

A is the containing box for the rheostat, of circular shape, as shown, and is made of a single thin metal casting provided with ribs upon its under side for strengthening it.

Within this box are arranged rows of contacts D, D, suitably insulated and connected by the resistance wires Q, Q, as shown in Fig. 4, to be more particularly described hereinafter.

C is the top of the box serving to cover its working parts and protect them from accidental injury and dirt.

B is the pedal, upon which the foot of the operator is supported, to which is secured the brush holder E serving to make the various connections of the rheostat in ways well understood. This pedel swings in a horizontal plane about a central pivot, as distinct from the vertical motion of the pedals usually provided; and by attaching it to a common pivot

with the brush holder E, the weight of the operator may be borne directly upon the pedal and its rotation about the center is effected with no more fatigue than an ordinary standing position would give. Within the brush holder are secured the parts giving an elastic

connection to the brush H, as seen in Figs. 2 and 3. The blocks F, F are hollowed out on their inside to afford a seat for the spring G acting to force the brush H into contact with the rows of rheostat contacts D, D. After 55 the blocks F are placed in position they are secured to the brush holder by screws passing through holes drilled in each of the boxes. The construction thus described renders it easy to replace the brush or spring should either one become damaged or worn.

Referring to Fig. 4, m, m, are the mains supplying current to the field magnet terminals M, M'. K, K are the coils of the motor field magnet and L is the armature supplied by 65 the current from the terminals M, M'. H, H, show the brushes which are connected by flexible cables I, I, with the armature terminals.

The course of the current is as follows: Entering by the main m to the field magnet terminal M, it passes to the contact plates a, a' which are connected by a copper wire O and then through the resistance wires to plate b, thence to plate b', then c, &c., to the plate e', supplying the brush H, which would be upon 75 the plate e'; the current then passes to the armature terminal N', then through the armature, then to the terminal N, then by the cable I to the second brush H, which would rest upon the contact plate g; then through 80 the resistance wires to the plate k', and by the copper wire O' to the field terminal M' and then out over the negative main. The field magnets being in shunt, the insertion of the resistance reduces the effective potential 85 on the armature, thus giving a low speed; but upon shifting the position of the brushes, more and more of the resistance is cut out until the brushes rest upon the contact plates a', k, in which position the resistance is all 90 cut out and the effective potential is a maximum, giving a very high speed to the motor.

In order to stop the motor quickly without the intervention of brakes, I provide a section of resistance wire between the contact 95 plates l, l, upon which the brushes normally stand; the result of this is that when the armature is short circuited through this resistance it is speedily brought to a standstill. To provide for a little lost motion in the 100

pedal, so that the operator may not start the motor inadvertently, idle contact plates f, f , &c., are provided upon each side of the normal position of the pedal. To run the motor in the opposite direction the motion of the pedal need only be reversed, in which case the current is passed through the armature in the reversed direction, while the field magnets being in shunt are energized in the same way.

Having thus described my invention, what I claim as new, and wish to protect by Letters Patent of the United States, is—

1. In a rheostat for controlling dental motors, a centrally pivoted pedal adapted to move a brush arm toward or away from a central position, and a short-circuiting resist-

ance for a motor at such central position, substantially as described.

2. In a rheostat for controlling dental motors, a centrally pivoted pedal adapted to move the brush arm toward or away from a central position, and idle contact plates as f, f , upon each side of such central position; whereby the arm may have a slight lost motion preventing the inadvertent starting of the motor.

In witness whereof I have hereunto set my hand this 7th day of July, 1893.

JONATHAN P. B. FISKE.
